Primary Examiner — Paula Greene

(57) **CLAIM**

The ornamental design for a communications headset, as shown and described.

DESCRIPTION

FIG. 1 is a top-front-right perspective view of a communications headset showing my new design;

FIG. 2 is a top-back-left perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a top-front-right perspective view showing a second embodiment of my new design;

FIG. 10 is a top-back-left perspective view thereof;

FIG. 11 is a front view thereof;

FIG. 12 is a back view thereof;

FIG. 13 is a left view thereof;

FIG. 14 is a right view thereof;

FIG. 15 is a top view thereof;

FIG. 16 is a bottom view thereof;

FIG. 17 is a top-front-right perspective view showing a third embodiment of my new design;

FIG. 18 is a top-back-left perspective view thereof;

FIG. 19 is a front view thereof;

FIG. 20 is a back view thereof;

FIG. 21 is a left view thereof;

FIG. 22 is a right view thereof;

FIG. 23 is a top view thereof; and,

FIG. 24 is a bottom view thereof.

The broken lines showing the unclaimed features form no part of the claimed design.

1 Claim, 24 Drawing Sheets
